Attorney

UNITED STATES PATENT OFFICE

DAVID P. DAVIES, OF RACINE, WISCONSIN, ASSIGNOR TO J. I. CASE COMPANY, OF RACINE, WISCONSIN, A CORPORATION

INTERNAL-COMBUSTION ENGINE

Application filed June 21, 1928. Serial No. 287,196.

My invention relates to internal combustion engines for use with tractors and other purposes, whereby I am enabled to attach to the engine block in a simple and precise manner such equipment as magnetos, governors and the like, and which is accomplished without the necessity of machining the surface of the projecting wall of the block to which, for example, it is desired to neatly fit a bracket for supporting a magneto in combination with a governor, which novel assemblage and support will be hereinafter more particularly described.

In the accompanying drawing, forming part hereof, Figure 1 is a fragmentary side elevation of an engine with my improvement shown in section; Fig. 2 a side elevation of the equipment, and Fig. 3 is a detail section taken on the dotted line 3—3 in Fig. 2.

In said drawing the numeral 5 indicates an engine-block embodying the usual crank-shaft, 6, having a driving gear, 7, thereon engaging gear, 8, on cam-shaft, 9, in a well known manner. The engine block embodies a laterally projecting wall, 10, forming part of a housing, 12, designed to support a magneto or other equipment usually mounted upon a bracket fitting tightly against the rear surface of the housing, which common arrangement has necessitated machining of such surface requiring considerable skilled labor and expense.

Extending rearwardly from the wall 10 is the wall 12, said walls constituting a housing having an oil inlet 13 at its upper side enclosed by a removable cap 14, and in the rear wall of said housing I provide an opening 15 for a purpose to appear. In the wall 10 is an opening 16 arranged in concentric relation to the opening 15 in the wall 12 of the housing, the latter being of less diameter. In said openings 15, 16, I insert a governor bearing carrier, 17, comprising the bearing heads 18, 19, and hollow body portion, 20, having an oil inlet, 21, through which oil passes from the inlet 13 into the body 20 and thence to the actuating devices beneath, and also through the outlets 22 in head 19 for lubricating parts communicating therewith.

In equipping the engine with a magneto

and governor I insert the governor bearing carrier 17 through the openings 16, 15, until the flange 23 on head 18 abuts against the gasket in housing 12, when the carrier will be snugly positioned in the openings 15, 16, as indicated in Fig. 1. To the outer flange 25 of the head 18 I secure a bracket 26 by means of bolts, as 27, the bracket being designed for the support of a magneto 28. In assembling a combined magneto as 28 and governor 29 upon the engine block I employ a shaft 30 which extends through the heads 18, 19, and carries a gear 32 which is driven by the crank-shaft gear 7 through the intermediary of the cam-shaft gear 8, said shaft 30 being provided with a collar 30' abutting against head 18 and a nut 33 for tightening the parts associated therewith. The outer end of the shaft is turned down, as at 34, Fig. 1, and upon which is mounted the governor 29 of any desired construction and operation. The gear 32 and parts associated therewith are enclosed by a casing 37 extending from the wall 10, and which casing is provided with a cover 38 which may be removed so that access may be readily had to the interior mechanism for inserting or withdrawing the carrier 17, or otherwise.

It is essential that the head 18 shall constantly tightly fit against the housing 12 and be held from rotation, and for which purpose I provide an adjusting screw 40 in the housing 12, which screw is tapered and enters an enlarged opening 41 in the body 21 of the governor bearing carrier, as clearly shown in Fig. 3. As said screw engages but one side of the wall forming said opening it will be readily understood that by tightening the screw the tapered end thereof will crowd and urge the carrier against the housing 12 so that the necessary tight fit between these parts may be maintained by simply turning the screw in the direction required for the purpose. By removing the cover 38 and the bolts 27 and releasing screw 40, it will be apparent that the assembly constituting the governor bearing carrier, shaft, gear and governor, can be readily removed and replaced at will as a unit and that the bracket 26 can be attached to the flange 25, the sur-

face of which may be machined before the carrier is inserted in the housing, so that there will be no necessity of machining the rear surface of housing 12, which latter operation is a difficult and expensive process when it is understood that the space occupied by said casing and its juncture with the engine block 5 provides but very limited area for the application of machining devices or tools.

10 In the manner shown and described it will be apparent that I use the housing wall 12 for supporting an equipment of the character explained without the necessity of machining the wall, as before stated, with the result that a compact assemblage of a magneto and governor or other equipment is inexpensively accomplished, and which may be readily installed and removed in a comparatively simple and expeditious manner.

15 I claim as my invention:

1. An engine block having a transverse wall embodying an opening, a wall associated with the first mentioned wall and having an opening therein, said walls constituting a housing and said openings being arranged concentrically, a governor bearing carrier insertible through said openings and supported by the housing, a support, and means for connecting said support to the carrier.

2. An engine block having a supporting wall, a wall associated with the supporting wall, said walls constituting a housing, a hollow governor bearing carrier embodying a head mounted in the housing, a bracket secured to the head, a magneto mounted upon the bracket, a shaft extending from the magneto through the carrier, means for driving the shaft, and a governor connected to and driven by the shaft.

3. An engine block having a housing comprising a supporting wall embodying an opening, a wall embodying an opening associated with the supporting wall, said openings being in concentric relation, a governor bearing carrier embodying heads mountable in said walls, a shaft extending through the heads, a gear on the shaft for driving the same, means for driving the gear, a casing enclosing the gear and driving means, and removable means for covering the casing.

4. An engine block having a housing comprising a rear wall embodying an opening and a forward wall having an opening of greater diameter than the rear wall opening, a governor bearing carrier embodying heads, a shaft and a gear insertible as a unit through the opening in the forward wall and seated in the opening of less diameter in the rear wall, said carrier having means for limiting its movement in relation to the rear wall, and a support secured to said carrier.

5. An engine block having a transverse wall embodying an opening, a wall associated with said first mentioned wall and having an

opening therein, said walls constituting a housing, a governor bearing carrier embodying an oil inlet and outlet mounted in said housing, a shaft passing through the bearing carrier, a gear on the shaft, means for securing the gear and shaft to the carrier, and adjusting means in the housing and engaging the carrier whereby the latter may be forced inwardly.

6. An engine block having a housing comprising a rear wall and a forward wall, said walls embodying concentric openings, an apertured hollow governor bearing carrier embodying heads mounted in the openings in said walls, a shaft extending through said heads, and means connected to the shaft whereby the latter is rotated from a source of power in the engine.

7. An engine block having an outer and an inner wall constituting a housing, said walls having openings arranged in concentric relation, a governor bearing carrier embodying a head removably mounted in said housing, a shaft mounted in the bearing carrier, a gear on the shaft, means on the shaft for securing the gear and bearing carrier thereon, and means in the carrier for inwardly forcing and maintaining its head against the housing.

8. In testimony whereof I affix my signature.

DAVID P. DAVIES.
